FEED AND TAIL STOCK FOR GRINDING
MACHINES

John Ryer Dunham, New Brunswick, N. J.

Application February 15, 1933, Serial No. 656,933

45 Claims. (Cl. 51—108)

My invention relates to grinding machines and especially to automatic grinding machines of the type disclosed in my application Serial No. 599,-782 filed March 10, 1932.

5 Primarily the invention has for an object to provide an automatic feeder and work rest for delivering stock from a magazine to its position to be worked upon by the grinding wheel, and then to deliver it from the machine.

10 Further it is an object to provide an automatic feeder which is rapid in its action, rugged in its construction, is so designed that it will work in harmony with the driving spindles of the centerless grinder disclosed in my application aforesaid.

15 Another object is to provide a feeder of the rotatable wheel type whose wheel is provided with a series of work rests, which provision allows larger lots of bearings to be ground without re-grinding the work rests than has heretofore been possible.

Another object is to provide a rotatable wheel-type feeder which, while the work is being operated upon by the grinding wheel, is rigidly locked against movement.

25 Further, it is an object to provide a feeder with cylindrical work rests which can be removed to change sizes when desired.

Further, it is an object to provide a feeder with multiple work rests which will handle work both for internal and external grinding.

30 Further, it is an object to provide a feeder which will locate the work to position by a synchronizer which is adjustable to allow work to be ground one-eighth smaller and one-eighth larger than work rests.

35 Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claims, reference being had to the accompanying drawings, in which:—

40 Figure 1—1A constitutes a plan view of so much of a grinding machine of the type of my application aforesaid as is necessary to show the present invention.

45 Figure 2 is a detail vertical cross section on the line 2—2 of Figure 1.

50 Figure 3 is a detail enlarged cross section on the line 3—3 of Figure 1, the gear train to the cam shaft being omitted.

Figure 4 is a detail side elevation looking from right to left in Figure 1.

Figure 5 is a vertical section on the line 5—5 of Figure 3.

Figure 6 is a detail view hereinafter referred to. 5

Figure 7 is a detail view of the adjustable stud for the synchronizing arm.

Figure 8 is a detail section on the line 3—3 of Figure 1 showing the gear train to the cam shaft.

Figure 9 is a front elevation and part section of 10 a portion of the machine.

Figure 10 is a detail view showing a modified way of driving the cam shaft from the mutilated gear.

15 In the drawings in which like numbers and letters of reference indicate like parts in all the figures, 1 represents the base of the machine on which is mounted the grinding wheel 2 and which has a pivot 3 for the pivot shaft 4 of the tail stock table 5. The table 5 has dovetailed ways 6 to 20 receive and guide the slide 8. The slide 8 is moved toward and from the wheel 2 by a feed screw (not shown) passing through the apron 9 and threaded into the apron 7 as in my application aforesaid, the screw being operated by the hand wheel 10 (Figure 1). All of the foregoing parts may be of the same construction as the corresponding parts in my application aforesaid. 25

30 Carried on the slide 8 are bearings 11 for the driving spindle 12, one end of which has a flanged collar 13, while the end adjacent the wheel 2 has a driving head 14 to engage the end of the piece of work 123 to be ground.

35 The spindle 12 is driven by sprocket and chain 15 from a suitably located counter shaft 16 mounted in bearings 17 beneath and on the slide 8 and driven in any suitable way from a prime moving shaft (not shown) of the machine.

40 18 is a cam whose shaft 21 is suitably mounted on the slide 8. The cam has an outer concentric groove 19 and an inner concentric groove 20, merging one with the other. The cam 18 effects the placing and withdrawing of spindle head 14 to and from the work.

45 The cam 18 is driven from a cam shaft 24 that is held in bearings 25 beneath the slide 8 by spiral gears 22—23 and acts on the spindle 12 through the medium of a bell-crank lever 43—45 whose roller 44 works in the grooves 19—20 and whose fork rollers work in the flanged collar 13. The 50 lever 43—45 is mounted on a stud 42 on the top of the slide 8.

55 Another bearing standard 26 is mounted on the slide 8 in alignment with bearings 11 and carries the thrust spindle 27 and its immediately asso- 55

ciated parts which are the front sleeve 30, spring 32 and the rear sleeve 31, the sleeve 30 and head 28 of the spindle having a thrust bearing 29.

The sleeve 31 is advanced and withdrawn by 5 a cam and lever device similar to that which operates spindle 12. The spindle 27 has a collar 34 pinned to its outer end against which the flanged collar 33 of the sleeve 31 abuts so that the cam and lever system may withdraw the 10 head 28 from the work when it is to be discharged and a new piece is to be brought into position.

The cam which operates the thrust spindle 27 is indicated by 35 and its shaft 39 is mounted on the slide 8. The shaft 39 is driven from shaft 15 24 in the same manner as shaft 21, i. e., by spiral gears 40—41. The cam 35 has an outer concentric groove 36, an inner concentric groove 37 and an intermediate groove 38, the latter merging with grooves 36—37 at its ends while the 20 grooves 36—37 at their other ends merge with one another. The spindle sleeve 31 is moved longitudinally in the bearing 26 by a second bell-crank lever 43—45, pivoted on a second stud 42 and having rollers 44 and 46 to engage the 25 grooves of cam 35 and the groove of collar 33 respectively. The cams 18 and 35 are so timed that the heads 14 and 28 move apart simultaneously to release the work, but not until cam 35 through its groove 38 has first released pressure 30 on head 28 by moving sleeve 31 outwardly to release the tension of the spring 32.

The cam shaft 24 is driven from the spindle 12 through a suitable gear train, which also drives the feed wheel that takes the work from a 35 magazine, locates it between spindle heads 14 and 28 and by the rotation of said heads is itself placed and held in position on the work rests, as will later more fully appear.

A master driving spur gear 47 on the spindle 40 12 meshes with a spur gear 48 on stud 49 that is secured at 50 in a bearing 51. The gear 48 may have a bearing bushing 52 if desired and it is interlocked at 54 with the continuously rotating element 53 of a one-revolution-and-stop 45 clutch mechanism, the driven element of which comprises a mutilated spur gear 59. The elements 53 and 59 have suitable bushings 55 and turn on the stud 49. The element 53 has a key groove 56 and element 59 has a key pocket 58 for the key 57 which, when projected, serves to lock the elements 53 and 59 together. The key is projected by a spring 60 held in the pocket 58 by a closure plate 61. The gear 59 has one-half of its teeth removed as at 62 and this portion has a locking arc-plate or segment 63 secured to the 55 side of the gear by screws 64.

The plate 63 cooperates with locking plates 65—65 on a spur gear 66 whose shaft 67 is mounted in a bearing 68 extended from the side 60 of the bearing 69 for the stub shaft 89 of the feed wheel 90.

Pivoted at 71 on the support 51 is a finger 70 having a beveled end 86 to release the key 57 from element 53 after each revolution of the element 59. The finger 70 is held in its operating position by a spring 72 secured to it and to a post 73. A bracket 74 is secured to the support 51 and has an opening through which the clutch control bar 75 passes and with which bracket it 70 has a pin 80 and slot 79 connection. The bar 75 has a head 77 and an abutment 76, the latter engaging the finger 70 when the bar 75 is moved to the right in Figure 3 to release the key 57. A spring 78 moves the bar 75 to free finger 70. 75 This act is accomplished as the operator turns

the hand wheel 10 to move slide 8 away from wheel 2. (The movement of slide 8 and wheel 2 apart may be done by automatic mechanism which forms no part of the present invention, if the invention is being used on a wholly automatic machine.)

The bar 75 may have a one-way-hinged dog 82 pivoted at 81 to engage a similar dog 83 hinged at 84 to the base 1 of the grinding wheel assembly. The dog 83 being held back by a stiff relief spring 10 85 of greater tension than that of the finger spring 72 but of such tension that it will allow dog 83 to give when pin 80 is engaged at left-hand end of slot 79 (Figure 3), should the slide 8 be run back too far.

A spur pinion 87 is secured on the shaft 67 and meshes with a spur gear 88 on the feed wheel shaft 89 to move the feed wheel one step at a time as gear 59 operates gear 66, as will later more fully appear.

The feed wheel 90 has a plurality of circular sockets 91 (six being shown, but more or less may be provided as desired), for the circular bodies 92 which carry the work rests 94—95, the bodies being held in place, if desired, by 25 screw keys 93 (Figure 2). The wheel 90 also has a set of synchronizing or locking notches 96 with which the tip 97 of the finger 98 of the synchronizer arm 99 engages. The arm 99 and its finger 98 move as one on a pivot 100 whose eccentric shank 101 is held in a bearing extension 102 by a set screw 103 (see Figure 7).

A synchronizing cam 104 is mounted on shaft 24 and cooperates with a connecting rod pivoted at 106 to arm 99 and having a strap 105 35 around the cam 104. The strap 105 has a tubular extension 109 in which is the shank 108 of a buffer plate 107 and a tension spring 110. An adjusting screw 111 is provided for the spring 110 to allow lost motion in the connection between cam 104 and wheel 90 while maintaining engagement of tip 97 with wheel 90 and notch 96.

The work pieces 123 are delivered to the high side of the wheel 90 by a magazine 112 and are guided from there to the wheel 2 by a top guide 45 113. They are delivered when finished into an off-take chute 114 to which they are guided from the wheel 90 by a lower guard 115.

Motion may be imparted to the shaft 24 directly from gear 59 through a sprocket and 50 chain connection 125, 126, 127 (Figure 10) or it may be done by providing a gear 116 on a stub shaft 117 to mesh with gear 59, the gear 116 having locking plates 118 and being similar to gear 66. The gear 116 meshes with a gear 55 119 on a shaft 120, supported at 121, and in turn meshing with a gear 122 on shaft 24 (Figure 8).

In the machine depicted in Figures 1 to 9, inclusive, the gear 59 has half the number of 60 teeth of gears 66 and 116 so that one revolution of gear 59 imparts a half revolution to gears 66 and 116. The ratios between gears 116, 119 and 122 are such that one-half revolution of gear 116 imparts one revolution to shaft 24.

The ratios of gears 66—87—88 are such that one-half revolution of gears 66—87 imparts a one-sixth revolution to gear 88 and hence to wheel 90.

Operation

Assume that a work piece is to be delivered to position for grinding and another has just been ground. The operator turns back wheel 10 to draw slide 8 away from grinding wheel 2. 75

This engages 82 and 83 and pulls bar 75 to the right in Figure 3, thereby releasing key 57 which, as soon as slot 56 lines up with it, will lock elements 53 and 59 together. In the meantime 82 and 83 will become disengaged and springs 72 and 78 will return finger 70 and bar 75 so that key 57 will be released again as one revolution of gear 59 is made.

As gear 59 begins to turn and just before cam 104 releases finger tip 97 from notch 96, cam groove 38 will cause lever 43—45, associated with it, to move sleeve 31 to the right to release tension of spring 32 and then engage collar 34.

As gear 59 moves farther, cams 18 and 35 will move spindles 12 and 27 apart, and cam 104 will release finger tip 97 from notch 96. By this time teeth on gear 59 will engage gear 66 and cause wheel 90 to be turned one step. Thereafter as gear 59 completes its single revolution cam 104 will cause 97 to enter the adjustment notch 96, and then cams 18 and 35 will move spindle heads 14—28 into engagement with the newly placed piece of work.

As wheel 90 moves its step just described the finished piece will drop onto chute 114 and be discharged from the machine. The operator then screws in on screw wheel 10 to move slide 8 toward grinding wheel to bring the new piece of work against the wheel 2 and the cycle of operation is complete.

It should be understood that in the machine illustrated the axis of the spindles 12 and 27 is preferably eccentric to that of the work and the work rests, as in the machine of my application aforesaid, so the spindles in rotating constantly tend to keep the work properly seated on the rests 94—95.

The rotatable feed wheel with its endless number or series of work rests, which is moved or indexed step by step to the grinding position, when it arrives at the grinding position locates itself accurately for the support of the work to be ground and supports that work during the entire grinding operation. When the driving spindles come in contact with the work all of the support of the work is taken by the work rest during the grinding operation due to the driving spindles being set off-center of the work which they drive, thus automatically drawing the work down in the rest during the grinding operation.

The invention is also adapted for use on certain boring machines as well as on other types of grinding machines than the particular one shown and I wish it clearly understood that changes in the details of construction and arrangement of parts may be made without departing from the spirit of the invention and the scope of the appended claims.

What I claim is:

1. In a grinder, a grinding wheel and a support, and means to effect relative movement between the wheel and support from and toward one another, a work magazine, a rotatable feed wheel, having a plurality of pockets in its circumference, a removably mounted work rest in each pocket open at the periphery of the wheel and arranged to receive the work from the magazine, work-end-engaging spindles adjacent the grinding wheel, means to lock the feed wheel with the work in position for grinding, and means to unlock the wheel and impart to it a step-by-step rotation at intervals to deliver new work to and remove finished work from the spindles.

2. In a grinder, a grinding wheel and a support,

and means to effect relative movement between the wheel and support from and toward one another, a work magazine, a rotatable feed wheel, having a plurality of pockets in its circumference, a removably mounted work rest in each pocket open at the periphery of the wheel and arranged to receive the work from the magazine, work-end-engaging spindles adjacent the grinding wheel, means to lock the feed wheel with the work in position for grinding, means to unlock the wheel and impart to it a step-by-step rotation at intervals to deliver new work to and remove finished work from the spindles, and means effected by the relative movement between the grinding wheel and said support for controlling the action of said feed wheel unlocking and rotating means.

3. In a grinding machine having a grinding wheel and work-holding spindles, the combination with the work-holding spindles, of a work-feeding wheel having a plurality of work rests spaced about its periphery, and mounted to convey work into and from position with respect to said spindles, means to hold the work between the spindles with yieldable pressure, and means first to release the pressure without disengaging the spindles from the work, then withdraw the spindles from the work, then rotate the feed wheel one step and then return the spindles to engagement with a new piece of work.

4. In a grinding machine having a grinding wheel and work-holding spindles, the combination with the work-holding spindles, of a work-feeding wheel having a plurality of work rests spaced about its periphery, and mounted to convey work into and from position with respect to said spindles, means to hold the work between the spindles with yieldable pressure, and means first to release the pressure without disengaging the spindles from the work, then withdraw the spindles from the work, then rotate the feed wheel one step and then return the spindles to engagement with a new piece of work, and means to move relatively the grinding wheel and work-holding spindles to and from each other, and means governed by said relative movement for controlling the action of said means first to release the pressure, then withdraw the spindles from the work, then rotate the feed wheel one step and then return the spindles to engagement with a new piece of work.

5. In a grinding machine, a grinding wheel and a support and means to effect relative movement between said wheel and support toward and from one another, work-holding spindles carried by the support, a magazine for work blanks, and means governed by the relative movement between said wheel and support in one direction for conveying work blanks one at a time to said spindles and removing finished work from the spindles.

6. In a grinding machine, a grinding wheel and a support and means to effect relative movement between said wheel and support toward and from one another, work-holding spindles carried by the support, a magazine for work blanks, a rotatable wheel carrying rests and adapted to receive a blank from the magazine, convey it to said spindles and support it while being ground by said grinding wheel and to remove the finished work from the spindles, means for driving said spindles, means including an intermittent clutch device and a gear train between said rotatable wheel and said driving means for actuating said rotatable wheel and means for effecting the intermitting action of said clutch device.

7. In a grinding machine, a grinding wheel and a support and means to effect relative movement between said wheel and support toward and from one another, work-holding spindles carried by the support, a magazine for work blanks, a rotatable wheel carrying rests and adapted to receive a blank from the magazine, convey it to said spindles and support it while being ground by said grinding wheel and to remove the finished work from the spindles, means for driving said spindles, means including a gear train and a one-revolution-and-stop clutch device connecting said driving means with said rotatable wheel to operate same, and means governed by said relative movement between said grinding wheel and said support for controlling said clutch device.

8. In a grinding machine, a grinding wheel and a support and means to effect relative movement between said wheel and support toward and from one another, work-holding spindles carried by the support, a magazine for work blanks, a rotatable wheel carrying rests and adapted to receive a blank from the magazine, convey it to said spindles and support it while being ground by said grinding wheel and to remove the finished work from the spindles, means for driving said spindles, means including an intermittent clutch device for actuating said rotatable wheel, means for effecting the intermitting action of said clutch device, said spindles including a yieldable member and engaging the work at its ends, and means for releasing the pressure of the yieldable member on the work before the rotatable wheel begins to turn.

9. In a grinding machine, a grinding wheel and a support and means to effect relative movement between said wheel and support toward and from one another, work-holding spindles carried by the support, a magazine for work blanks, a rotatable wheel carrying rests and adapted to receive a blank from the magazine, convey it to said spindles and support it while being ground by said grinding wheel and to remove the finished work from the spindles, means for driving said spindles, means including a gear train and a one-revolution-and-stop clutch device connecting said driving means with said rotatable wheel to operate same, means governed by said relative movement between said grinding wheel and said support for controlling said clutch device, said spindles including a yieldable member and engaging the work at its ends, and means for releasing the pressure of the yieldable member on the work before the rotatable wheel begins to turn.

10. In a grinding machine, a grinding wheel and a support and means to effect relative movement between said wheel and support toward and from one another, work-holding spindles carried by the support, a magazine for work blanks, means governed by the relative movement between said wheel and support in one direction for conveying work blanks one at a time to said spindles and removing finished work from the spindles, said spindles including a yieldable member and engaging the work at its ends, and means for releasing the pressure of the yieldable member on the work without disengaging the spindles from the work and before said governed means begins to act, and for thereafter separating the spindles to release the finished work and then bringing them together again to hold a newly placed blank in position for grinding.

11. In a grinding machine, a grinding wheel and a support and means to effect relative movement between said wheel and support toward

and from one another, work-holding spindles carried by the support, a magazine for work blanks, a rotatable wheel carrying rests and adapted to receive a blank from the magazine, convey it to said spindles and support it while being ground by said grinding wheel and to remove the finished work from the spindles, means for driving said spindles, means including an intermittent clutch device for actuating said rotatable wheel, means for effecting the intermitting action of said clutch device, said spindles including a yieldable member and engaging the work at its ends, and means for releasing the pressure of the yieldable member on the work without disengaging said yieldable member from the work and before the rotatable wheel begins to turn, and for thereafter separating the spindles to release the finished work and then bringing them together again to hold a newly placed blank in position for grinding.

12. In a grinding machine, a grinding wheel and a support and means to effect relative movement between said wheel and support toward and from one another, work-holding spindles carried by the support, a magazine for work blanks, a rotatable wheel carrying rests and adapted to receive a blank from the magazine, convey it to said spindles and support it while being ground by said grinding wheel and to remove the finished work from the spindles, means for driving said spindles, means including a gear train and a one-revolution-and-stop clutch device connecting said driving means with said rotatable wheel to operate same, means governed by said relative movement between said grinding wheel and said support for controlling said clutch device, said spindles including a yieldable member and engaging the work at its ends, and means for releasing the pressure of the yieldable member on the work before the rotatable wheel begins to turn, and for thereafter separating the spindles to release the finished work and then bringing them together again to hold a newly placed blank in position for grinding.

13. In a grinding machine having a grinding wheel and work-holding spindles, the combination with the work-holding spindles, of a work-feeding wheel having a plurality of work rests spaced about its periphery, and mounted to convey work into and from position with respect to said spindles, means to hold the work between the spindles with yieldable pressure, and means first to release the pressure without disengaging the spindles from the work, then withdraw the spindles from the work, then rotate the feed wheel one step and then return the spindles to engagement with a new piece of work, means to lock said work-feeding wheel while the work is being ground, and means to release said locking means when the feeding wheel is to be turned.

14. In a grinding machine having a grinding wheel and work-holding spindles, the combination with the work-holding spindles, of a work-feeding wheel having a plurality of work rests spaced about its periphery, and mounted to convey work into and from position with respect to said spindles, means to hold the work between the spindles with yieldable pressure, and means first to release the pressure without disengaging the spindles from the work, then withdraw the spindles from the work, then rotate the feed wheel one step and then return the spindles to engagement with a new piece of work, and means to move relatively the grinding wheel and work-holding spindles to and from each other, and means gov-

erned by said relative movement for controlling the action of said "means first to release the pressure without disengaging the spindles from the work, then withdraw the spindles from the work, then rotate the feed wheel one step and then return the spindles to engagement with a new piece of work", means to lock said work-feeding wheel while the work is being ground, and means to release said locking means when the feeding wheel is to be turned.

15. In a grinding machine, a grinding wheel and a support and means to effect relative movement between said wheel and support toward and from one another, work-holding spindles carried by the support, a magazine for work blanks, a rotatable wheel carrying rests and adapted to receive a blank from the magazine, convey it to said spindles and support it while being ground by said grinding wheel and to remove the finished work from the spindles, means for driving said spindles, means including an intermittent clutch device and a gear train between said rotatable wheel and said driving means for actuating said rotatable wheel and means for effecting the intermittent action of said clutch device, and means to lock said rotatable wheel while the work is being ground and to release said wheel when it is to be turned.

16. In a grinding machine having a grinding wheel and work-holding spindles, the combination with the work-holding spindles of a work-feeding wheel having a plurality of work rests spaced about its periphery, and mounted to convey work into and from position with respect to said spindles, means to hold the work between the spindles with yieldable pressure, and means first to release the pressure without disengaging the spindles from the work, then withdraw the spindles from the work, then rotate the feed wheel one step and then return the spindles to engagement with a new piece of work, means to lock said work-feeding wheel while the work is being ground, and means to release said locking means when the feeding wheel is to be turned, said locking and releasing means comprising a notch in the feeding wheel, an arm having a finger to fit said notch, a cam and connecting rod for operating said arm and finger and means to actuate said cam in harmony with the actuation of said feeding wheel.

17. In a grinding machine having a grinding wheel and work-holding spindles, the combination with the work-holding spindles of a work-feeding wheel having a plurality of work rests spaced about its periphery, and mounted to convey work into and from position with respect to said spindles, means to hold the work between the spindles with yieldable pressure, and means first to release the pressure without disengaging the spindles from the work, then withdraw the spindles from the work, then rotate the feed wheel one step and then return the spindles to engagement with a new piece of work, and means to move relatively the grinding wheel and work-holding spindles to and from each other, and means governed by said relative movement for controlling the action of said "means first to release the pressure without disengaging the spindles from the work, then withdraw the spindles from the work, then rotate the feed wheel one step and then return the spindles to engagement with a new piece of work", means to lock said work-feeding wheel while the work is being ground, and means to release said locking means when the feeding wheel is to be turned,

said locking and releasing means comprising a notch in the feeding wheel, an arm having a finger to fit said notch, a cam and connecting rod for operating said arm and finger and means to actuate said cam in harmony with the actuation of said feeding wheel.

18. In a grinding machine having a grinding wheel, a slide, means to move said slide toward and from said wheel, a pair of work-end-engaging and holding spindles mounted to rotate in bearings on said slide, means to drive at least one spindle, yieldable means for holding one of said spindles against the work, cam and lever mechanisms for moving said spindles along their axes toward and from the work, the cam which moves the spindle that has the yieldable means having provision for releasing the pressure of the yieldable means before beginning the movement of that spindle away from the work, a cam shaft geared to said cams, a work-blank-holding magazine, a rotatable wheel having a plurality of work rests and mounted on said slide to receive blanks from said magazine and to carry them to a position to be engaged by said spindles and be worked on by said grinding wheel, and means to impart a step-by-step movement to said rotatable wheel and said cam shaft.

19. In a grinding machine having a grinding wheel, a slide, means to move said slide toward and from said wheel, a pair of work-end-engaging and holding spindles mounted to rotate in bearings on said slide, means to drive at least one spindle, yieldable means for holding one of said spindles against the work, cam and lever mechanisms for moving said spindles along their axes toward and from the work, the cam which moves the spindle that has the yieldable means having provision for releasing the pressure of the yieldable means before beginning the movement of that spindle away from the work, a cam shaft geared to said cams, a work-blank-holding magazine, a rotatable wheel having a plurality of work rests and mounted on said slide to receive blanks from said magazine and carry them to a position to be engaged by said spindles and be worked on by said grinding wheel, and means to impart a step-by-step movement to said rotatable wheel and said cam shaft, said last-named means comprising a gear train including an intermittent clutch connecting the driving spindle with said rotatable wheel and with said cam shaft, and means to control the action of said clutch.

20. In a grinder, a grinding wheel and a support, and means to effect relative movement between the wheel and support from and toward one another, a work magazine, a rotatable feed wheel, having a plurality of pockets in its circumference, a work rest in each pocket arranged to receive the work from the magazine, work-end-engaging spindles adjacent the grinding wheel, means to lock the feed wheel with the work in position for grinding, means to unlock the wheel and impart to it a step-by-step rotation at intervals to deliver new work to and remove finished work from the spindles, and means cooperative with said locking means for holding the feed wheel slightly in advance of or retarded from its normal positions as desired for over and under size work.

21. In a grinder, a grinding wheel and a support and means to effect relative movement between said wheel and said support toward and from one another, work-holding spindles carried by the support, a magazine for work blanks, and

- an endless series of work rests, means for moving said work rests from a position to receive work from said magazine to a position for locating work with relation to said spindles and grinding wheel and means governed by the relative movement between said wheel and said support for actuating said work-rest-moving means for the purposes described. 5
22. In a grinder, a grinding wheel and a support 10 and means to effect relative movement between said wheel and said support toward and from one another, work-holding spindles carried by the support, a magazine for work blanks, and an endless series of work rests, means for moving 15 said work rests from a position to receive work from said magazine to a position for locating work with relation to said spindles and grinding wheel, means governed by the relative movement between said wheel and said support for actuating 20 said work-rest-moving means for the purposes described and means cooperative with said work rests for holding them in normal operative position while the work is being ground. 25
23. In a grinder, a grinding wheel and a support 30 and means to effect relative movement between said wheel and said support toward and from one another, work-holding spindles carried by the support, a magazine for work blanks, and an endless series of work rests, means for moving said work rests from a position to receive work from 35 said magazine to a position for locating work with relation to said spindles and grinding wheel, means governed by the relative movement between said wheel and said support for actuating said work-rest-moving means for the purposes described, means cooperative with said work rests for holding them in normal operative position while the work is being ground and means cooperative with said last-named means for advancing 40 or retarding the position of said work rests with respect to the normal for over and under size work. 45
24. In a grinding machine, a grinding wheel and a support, work-holding spindles carried by the support, a magazine for work blanks, means including work supports for conveying work blanks one at a time to said spindles and removing finished work from the spindles, said spindles including a yieldable member and engaging the work solely at its ends, and means for releasing the pressure of the yieldable member on the work without disengaging said spindles from the work and before the said conveying means begins to act, and for thereafter separating the spindles to release the finished work and then bringing them together again to hold a newly placed blank 50 in position for grinding. 55
25. In a grinding machine, a grinding wheel, a support, work-holding spindles carried by the support, a magazine for work blanks, a rotatable wheel carrying rests and adapted to receive a blank from the magazine, convey it to said spindles and support it while being ground by said grinding wheel and to remove the finished work from the spindles, means for driving said spindles, means including an intermittent clutch device for actuating said rotatable wheel, means for effecting the intermitting action of said clutch device, said spindles including a yieldable member and engaging the work at its ends, and means for releasing the pressure of the yieldable member on the work without disengaging said spindles from the work and before the rotatable wheel begins to turn, and for thereafter separating the spindles to release the finished work and then bringing them together again to hold a newly placed blank 60 in position for being worked on. 65
26. In a grinding machine, a grinding wheel and a support, work-holding spindles carried by the support, a magazine for work blanks, means including work supports for conveying work blanks one at a time to said spindles and removing finished work from the spindles, said spindles adapted to engage the work solely at its ends and including a yieldable member, a cam actuated means for releasing the pressure of said yieldable member on the work without disengaging the spindles from the work and subsequently separating said spindles to release the work therefrom and thereafter bring the spindles together again to hold a newly placed blank 70 in position for grinding. 75
27. A support, work-holding spindles carried by the support, a magazine for work blanks, means including work supports for conveying work blanks one at a time to said spindles and removing finished work from the spindles, said spindles including a yieldable member and engaging the work solely at its ends, and means for releasing the pressure of the yieldable member on the work without disengaging said spindles from the work and before the said conveying means begins to act, and for thereafter separating the spindles to release the finished work and then bringing them together again to hold a newly placed blank 80 in position for being worked on. 85
28. A support, work-holding spindles carried by the support, a magazine for work blanks, a rotatable wheel carrying rests and adapted to receive a blank from the magazine, convey it to said spindles and support it while being worked on and to remove the finished work from the spindles, means for driving said spindles, means including an intermittent clutch device for actuating said rotatable wheel, means for effecting the intermitting action of said clutch device, said spindles including a yieldable member and engaging the work at its ends, and means for releasing the pressure of the yieldable member on the work without disengaging said spindles from the work and before the rotatable wheel begins to turn, and for thereafter separating the spindles to release the finished work and then bringing them together again to hold a newly placed blank 90 in position for being worked on. 95
29. A support, work-holding spindles carried by the support, a magazine for work blanks, means including work supports for conveying work blanks one at a time to said spindles and removing finished work from the spindles, said spindles adapted to engage the work solely at its ends and including a yieldable member, a cam actuated means for releasing the pressure of said yieldable member on the work without disengaging the spindles from the work and subsequently separating said spindles to release the work therefrom and thereafter bring the spindles together again to hold a newly placed blank 100 in position for being worked on. 105
30. A work magazine, a rotatable feed wheel having a plurality of pockets in its circumference, a removably mounted work rest in each pocket open at the periphery of the wheel and arranged to receive the work from the magazine, work-end-engaging spindles, means to lock the feed wheel with the work in position for being worked on, and means to unlock the wheel and impart to it a step-by-step rotation at intervals 110 115 120

to deliver new work to and remove finished work from the spindles.

31. A work magazine, a rotatable feed wheel having a plurality of pockets in its circumference, 5 a removably mounted work rest in each pocket open at the periphery of the wheel and arranged to receive the work from the magazine, work-end-engaging spindles, means to lock the feed wheel with the work in position for being worked on, and means to unlock the wheel and impart to it a 10 step-by-step rotation at intervals to deliver new work to and remove finished work from the spindles, and means for controlling the action of said feed wheel unlocking and rotating means.

15 32. The combination with work-holding spindles, of a work-feeding wheel having a plurality 15 of work rests spaced about its periphery, and mounted to convey work into and from position with respect to said spindles, means to hold the 20 work between the spindles with yieldable pressure, and means first to release the pressure without disengaging the spindles from the work, then withdraw the spindles from the work, then rotate the feed wheel one step and then return the spindles to engagement with a new piece of work.

25 33. The combination with work-holding spindles, of a work-feeding wheel having a plurality 25 of work rests spaced about its periphery, and mounted to convey work into and from position 30 with respect to said spindles, means to hold the work between the spindles with yieldable pressure, means first to release the pressure without disengaging the spindles from the work, then withdraw the spindles from the work, then rotate the feed wheel one step and then return the spindles to engagement with a new piece of work, and 35 means for controlling the action of said work-holding means first to release the pressure, then to withdraw the spindles from the work, then to rotate the feed wheel one step, and then to return the spindles to engage a new piece of work.

40 34. A support, work-holding spindles carried 40 by the support, a magazine for work blanks, a rotatable wheel carrying rests and adapted to receive a blank from the magazine, convey it to said 45 spindles and support it while being worked on, and to remove the finished work from the spindles, means for driving said spindles, means including a gear train and a one-revolution-and-stop clutch device connecting said driving means with said rotatable wheel to operate same, and 50 means for controlling said clutch device.

45 35. A support, work-holding spindles carried 55 by the support, a magazine for work blanks, a rotatable wheel carrying rests and adapted to receive a blank from the magazine, convey it to said spindles and support it while being worked on, and to remove the finished work from the spindles, means for driving said spindles, means including an intermittent clutch device for actuating 60 said rotatable wheel, means for effecting the intermittent action of said clutch device, said spindles including a yieldable member and engaging the work at its ends, and means for releasing the pressure of the yieldable member on the work without disengaging said yieldable member from the work and before the rotatable wheel begins to turn, and for thereafter separating the spindles to release the finished work and then bringing them together again to hold a newly placed blank in position for being worked on.

70 36. A support, work-holding spindles carried 70 by the support, a magazine for work blanks, a rotatable wheel carrying rests and adapted to receive a blank from the magazine, convey it to

said spindles and support it while being worked on, and to remove the finished work from the spindles, means for driving said spindles, means including a gear train and a one-revolution-and-stop-clutch device connecting said driving means with said rotatable wheel to operate same, means for controlling said clutch device, said spindles including a yieldable member and engaging the work at its ends, and means for releasing the pressure of the yieldable member on the work before the rotatable wheel begins to turn, and for thereafter separating the spindles to release the finished work and then bringing them together again to hold a newly placed blank in position for being worked on.

10 37. The combination with work-holding spindles, of a work-feeding wheel having a plurality 10 of work rests spaced about its periphery, and mounted to convey work into and from position with respect to said spindles, means to hold the work between the spindles with yieldable pressure, and means first to release the pressure without 15 disengaging the spindles from the work, then withdraw the spindles from the work, then rotate the feed wheel one step and then return the spindles to engagement with a new piece of work, 20 means to lock said work-feeding wheel while the work is being worked on, and means to release said locking means when the feeding wheel is to be turned.

25 38. The combination with work-holding spindles, of a work-feeding wheel having a plurality 25 of work rests spaced about its periphery, and mounted to convey work into and from position 30 with respect to said spindles, means to hold the work between the spindles with yieldable pressure, and means first to release the pressure without 35 disengaging the spindles from the work, then withdraw the spindles from the work, then rotate the feed wheel one step and then return the spindles to engagement with a new piece of work, 40 means to lock said work-feeding wheel while the work is being worked on, means to release said locking means when the feeding wheel is to be turned, said locking and releasing means comprising a notch in the feeding wheel, an arm 45 having a finger to fit said notch, a cam and connecting rod for operating said arm and finger, and means to actuate said cam in harmony with the actuation of said feeding wheel.

50 39. A pair of work-end-engaging and holding spindles mounted to rotate in bearings on said support, means to drive at least one spindle, yieldable means for holding one of said spindles against the work, cam and lever mechanisms for moving said spindles along their axes toward 55 and from the work, the cam which moves the spindle that has the yieldable means having provisions for releasing the pressure of the yieldable means before beginning the movement of that spindle away from the work, a cam shaft geared to said cams, a work-blank-holding magazine, a rotatable wheel having a plurality of work rests and mounted on said support to receive blanks from said magazine and carry them to a position 60 to be engaged by said spindles and be worked on, and means to impart a step-by-step movement 65 to said rotatable wheel and said cam shaft.

70 40. A pair of work-end-engaging and holding spindles mounted to rotate in bearings on said support, means to drive at least one spindle, yieldable means for holding one of said spindles against the work, cam and lever mechanisms for moving said spindles along their axes toward and from the work, the cam which moves the spindle

- that has the yieldable means having provisions for releasing the pressure of the yieldable means before beginning the movement of that spindle away from the work, a cam shaft geared to said 5 cams, a work-blank-holding magazine, a rotatable wheel having a plurality of work rests and mounted on said support to receive blanks from said magazine and carry them to a position to be engaged by said spindles and be worked on, means 10 to impart a step-by-step movement to said rotatable wheel and said cam shaft, said last named means comprising a gear train including an intermittent clutch connecting the driving spindle with said rotatable wheel and with said cam shaft, and means to control the action of said clutch. 15
41. A support, a work magazine, a rotatable feed wheel having a plurality of pockets in its circumference, a work rest in each pocket arranged to receive the work from the magazine, work-end-engaging spindles, means to lock the feed wheel with the work in position for being operated on, means to unlock the wheel and impart to it a step-by-step rotation at intervals to 20 deliver new work to and remove finished work from the spindles, and means cooperative with said locking means for holding the feed wheel slightly in advance of or retarded from its normal positions as desired for over and under size work. 25
42. A support, work-holding spindles carried by the support, a magazine for work blanks, and an endless series of work rests, means for moving said work rests from a position to receive work 30 from said magazine to a position for locating work with relation to said spindles, means for actuating said work-rest-moving means, means cooperative with said work rests for holding them in normal operative position while the work is being worked on, and means cooperative with 35 said last named means for advancing or retarding the position of said work rests with respect to the normal for over and under size work. 40
43. A support, work-holding spindles carried 45 by the support, a magazine for work blanks, a
- rotatable wheel carrying rests and adapted to receive a blank from the magazine, convey it to said spindles and support it while being worked on, and to remove the finished work from the spindles, means for driving said spindles, means including an intermittent clutch device and a gear train between said rotatable wheel and said driving means for actuating said rotatable wheel and means for effecting the intermitting action of said clutch. 5
44. In a grinding machine, a grinding wheel and a support, work-holding spindles carried by the support, means for conveying work blocks one at a time to said spindles and removing finished work from the spindles, one of said 10 spindles comprising a thrust spindle, a front sleeve on said thrust spindle, said thrust spindle having a work engaging head against which said front sleeve operates, a rear sleeve on said thrust spindle, a spring between said sleeves, a cam actuated means for moving said rear sleeve and thrust spindle first to release the spring pressure and then move said thrust spindle lengthwise whereby pressure on said front sleeve is released before said thrust spindle is moved to disengage 15 the work. 20
45. In a grinding machine, a grinding wheel and a support, work holding spindles carried by the support, a magazine for work blanks, indexing means including work supports for conveying 25 work blanks one at a time to said spindles and removing finished work from the spindles, said spindles having provisions for engaging the work blanks only by end contact therewith, one of said spindles including a yieldable member for applying end pressure to hold the work blank between the spindles, means for releasing the pressure of the yieldable member before breaking contact between the spindle ends and the yieldable member and for separating the spindles after the 30 indexing operation starts to release the finished work, and means for subsequently moving the spindles together again to hold a newly placed blank in position for grinding. 35

JOHN RYER DUNHAM. 45
